UNITED STATES PATENT OFFICE.

HERMAN D. SCHNEIDER, OF BRUNNER, ONTARIO, CANADA.

ELEVATING LOADER.

Application filed May 2, 1921. Serial No. 466,190.

To all whom it may concern:

Be it known that I, HERMAN D. SCHNEIDER, of Brunner, in the county of Perth, Province of Ontario, Canada, a subject of the King of 5 Great Britain, have invented certain new and useful Improvements in Elevating Loaders, of which the following is a specification.

This invention relates to devices for picking up hay, grain or similar cut crops from 10 the field and loading it into a wagon or other receptacle and particularly to apparatus specially adapted for elevating and loading sheaves from the shocks, and my object is to devise apparatus of this kind which 15 is complete in itself, except for its power plant, and means of propulsion, and which is adapted to be coupled up with a suitable tractor, such as may be purchased in the open market, so that it may be propelled by 20 said tractor and its elevation and conveying mechanism driven therefrom.

I attain my object by means of the constructions hereinafter described and illustrated in the accompanying drawings in 25 which—

Fig. 1 is a side elevation of the loader;

Fig. 2 a front elevation of the same;

Fig. 3 a plan view of the same with parts removed; and

Fig. 4 a detail in perspective of the spring suspension for the front axle.

In the drawings like numerals of reference indicate corresponding parts in the different figures.

The frame of the loader comprises side members 1 suitably connected by transverse members and formed preferably of structural steel angles. These side members are arched intermediate their ends to give the 35 center of the frame greater clearance from the ground than towards the ends to avoid any possibility of the frame striking knolls or bumps which may be straddled by the supporting wheels of the apparatus. Preferably the arch is formed by using short 40 lower sills 2 at the under side of the side members of the frame which are connected by the inclined members 7 with the upper sill of the side frame. A longitudinal brace 45 4 connects these inclined members as shown to give proper strength at the otherwise weak point where the inclined members meet the upper sill of the side frame. Other arrangements might, of course, be used to provide 50 the necessary arch. This arch is particularly necessary in view of the adjustable

spring suspensions for the steering wheels and rear wheels of the frame which I will now describe.

The rear wheels 5 are journalled on stub 60 axles 6. Each stub axle is carried by a supporting bracket comprising a plate 7 and braces 8 to which the stub axle is connected. The plate 7 is vertically movable in guides 9 formed on the side member of the frame. 65 A spring suspension is provided between each stub axle supporting bracket and the frame. In the preferred construction a semi-elliptic spring 10 is secured intermediate its ends in any suitable manner to the 70 stub axle. One end of each spring is pivotally connected at 11 to the side member of a frame, which the other is preferably supported by a pivoted shackle 12 to compensate for the lengthening and shortening of the 75 spring under varying loads.

The forward end of the frame is provided with steering wheels 13 which are journalled in a manner known in the art on spindles 14 80 journalled on vertical axes 15 at the ends of the front axle 16. A spring suspension is

provided for this front axle, which preferably comprises the semi-elliptic springs 17 secured to the axle in a known manner. One end of each spring is pivotally connected to 85 the frame, while the other end is connected with a pivoted shackle 18 forming a compensating connection to take care of my varying lengths of the spring due to variations in load. The shackle is pivotally connected with a vertical bar 19, which is 90

slidable in suitable guides formed on the side member of the frame. The bent brace 20 is also provided supporting the outer side of the shackle. The other end of the spring is 95 connected with a pivot bolt 21 adapted to pass through any one pair of holes formed in the vertical members 22 connected to the side member of the loader frame. The position of the frame relative to the spring is 100 thus readily adjustable by altering the position of the bolt pivot 21 and by vertically adjusting the slidable bar 19.

Any suitable means may be provided for vertically adjusting this bar. I show the 105 bar as having a rack 23 formed at its upper end, with which rack engages a pinion 24 secured to a spindle 25 journalled on the side member of the frame of the machine and having a worm wheel 26 secured thereto. With this worm wheel 26 meshes a suitably journalled worm 27 on the spindle 28,

which leads to a position for convenient operation as hereinafter described. The spindle 25, it will be noted extends across the machine, where the pinion 24 and the rack 23 are duplicated so that both springs 17 may be simultaneously adjusted.

Suitably connected to the forward end of the frame is the frame 29 of the elevator. This elevator is of ordinary type provided 10 with elevator slats 30 connected to the chain 31 carried by suitable sprocket wheels 32 journaled at the top and bottom of the frame. A suitable picker drum 100 is journaled at the lower end of the elevator, 15 which may be of any type, such, for example as that shown in my prior Patent No. ——.

Suitably supported from the main frame and the elevator frame is the transverse conveyor 34, which may be of any ordinary 20 type such, for example, as that shown in the prior Patent 1,255,470, Feb. 5, 1918, hereinbefore referred to.

The shaft 35 carrying the upper sprockets 32 forms the drive shaft for the conveyor 25 and elevator system and this shaft is driven as hereinafter described. This shaft is connected with a shaft 36, preferably by means of a universal joint 37, and this shaft 36 is connected by means of a universal joint 38 30 with a shaft 39 journaled on the frame of the conveyor 34. This shaft 39, by means of bevel gearing 40, actuates the spindle 41 carrying the driving sprockets 42 of the transverse conveyor.

35 An important feature of my invention is the provision for propelling the same and for driving the elevator and conveyor. I employ as the power plant an ordinary tractor. The tractor is received within the frame 40 at the rear of the machine and is coupled so as to float relative to the loader frame. At the rear end of the frame is located a gate 43 comprising a cross member formed of suitable angles suitably connected and 45 secured to the side members 1 of the loader frame by means of removable bolts 44. Diagonal braces 45 are provided, extending from the cross members of the gate to the side members 1 to which they are secured 50 by removable bolts 46. By removing the bolts at one end of the gate and by also removing the bolts between the braces 45 and the side members 1, the gate may be swung wide open to permit of the entrance of the 55 tractor. The fore wheels of the tractor are removed and the forward end of the tractor is supported loosely on the frame of the machine. For this purpose I provide the transverse yoke member 47 which has its 60 ends rounded to form journals and supported in open bearing members 48 secured to the side members 1 of the loader frame. This yoke is provided centrally with an up-standing lug 49 adapted to be received between lugs 50 formed on a bracket secured

beneath the forward end of the tractor. A king pin 51 passes through the lugs. While the tractor is thus supported by the yoke member, it is free to rock laterally relative thereto, which rocking movement of the 70 tractor and the loader frame relative to one another is provided for by the journalling of the ends of the yoke member. The bearings being open above the yoke, the member is easily dropped into place. To tie the 75 side members 1 of the loader frame together beneath the tractor, I provide the transverse brace 52 suitably connected to the lower sills of the side members 1. The rear end of the tractor is provided with the usual draw bar 80 connection 53, which, when the tractor is in place within the frame, is bolted to the draw bar 54 which curves upwardly and rearwardly and is adapted to slide vertically on two guide members 55 secured to the gate. 85 Coil springs 56 are preferably placed about these guides and engage the underside of the top member of the gate and the upper side of the draw bar, so that a certain amount of the weight of the rear end of the loader 90 frame is taken by the draw bar. Diagonal braces 57 are bolted to the draw bar 54 and to the rear end of the tractor as shown to assist in taking the strain due to the downward pressure of the coil springs 56. From 95 the construction described it will be seen that the tractor as a whole is floatingly supported relative to the loader frame and at the same time is effectively coupled to the frame so that its power may be used to propel the latter, which is, however, supported substantially only by its own ground wheels. 100

The tractor is preferably so positioned that the axis of its master wheels 58 is substantially in the same vertical plane as the 105 axis of the stub axles 6 or at any rate not very far therefrom, as this facilitates the steering of the device by the steering wheels 13.

The arrangement described provided as 110 effectively for the propulsion of the apparatus as if the power plant were built into the latter, while the tractor, not being permanently a part of the machine, is always available for other service when not 115 required in connection with the loader.

It is important that the device as a whole, including the tractor, be controlled from a position where the operator has a full view of both the positions of the work to be effected and also of the discharge end of the transverse conveyor. I therefore provide an operator's platform 59 at the left hand side of the upper end of the elevator and in front of the transverse conveyor, this platform being suitably supported from the frame. To this platform all the controls of the apparatus are led. For instance, the spindle 28 for adjusting the vertical slide bar 19 is led to this platform and is provided 120

- with the operating wheel 60. A steering wheel 61 is also located in a convenient position at this platform and is connected with a suitably journaled steering spindle 62. 5 The lower end of this spindle is journaled in the frame of the loader and has a gear pinion 63 secured thereto which meshes with a pinion 64 on a spindle 65 which carries a worm meshing with a worm wheel 66 on the 10 spindle 67, to which is secured the rock arm 68, which, by means of a connecting rod 69, is connected with the connecting rod 70 connecting the steering arms 71 of the spindles 14 carrying the steering wheels. This mechanism is, of course, old in the art and may be arranged in many ways. So also various engine controls may be led to the operator's 15 platform 59. As these may be arranged in many different ways, I show only one in 20 detail, viz. the controlling means for the gear shift lever 72 of the tractor, which will usually be of the ordinary type in which the gears are shifted laterally by fore and aft movements of the lever. An upward extension 73 is bolted to the ordinary gear shifting lever and to this lever is pivotally connected an operating rod, the upper end 74 of which is located in a position convenient to the operator's platform. This rod 30 is provided with a lateral crank 75, which is adapted to both rock and slide laterally in brackets 76 secured to the loader frame. 35 To the end of the portion 75 is integrally or otherwise connected a depending portion 77, which in turn connects with a rearwardly extending portion 78, which is pivotally connected with the upper end of the extension 73 and the gear shift lever. This portion 78 is slidable in a guide 79 secured to the frame. 40 The guide 79 also serves as a fulcrum on which the portion 78 may rock in a substantially horizontal plane. It is evident that by pushing the upper end 74 of the operating lever laterally that the gear shift 45 lever will be pushed laterally, and that by rocking the upper end 74 either backwards or forwards the gear shift lever will be correspondingly rocked.
- To drive the elevator and conveyor I provide the following mechanism. A sprocket wheel 80 is secured to each master wheel 50 58 of the tractor, which sprocket wheels are connected by means of sprocket chains 82 with sprocket wheels 83 which are loose on the shaft 84 journaled on the loader frame. Each sprocket chain is provided with a 55 grooved tightener pulley 97 journaled on an arm 98 pivoted on the frame of the machine. These arms are held in engagement 60 with the sprocket chains to take up slack by means of coil springs 99 each connected at one end with one of the arms and at the other end with the frame of the loader. 65 Clutches 85 of the ordinary sliding spring actuated type are provided whereby the
- sprocket wheels may be given a driving connection with the shaft. This shaft carries a belt pulley 86 which drives a belt 87, which in turn drives a pulley 88 on the shaft 35 which carries the upper sprocket wheels 70 75 32 of the elevator, thus driving the elevator and from it the lateral conveyor as hereinbefore described. The clutches 85 are controlled from the operator's platform in the following manner. A T-shaped pivoted 75 clutch shift lever 90 suitably pivoted on the frame of the machine directly engages one of the clutches. With an upward extending arm 80 on this clutch shift lever a rod 91 is pivotally connected, which is forked at its other end and engages a collar 92 carried by the usual grooved collar of the far clutch. To the arm 93 of the clutch shift lever is pivotally connected the operating rod 94, which leads up to a suitable means for holding it in either 85 the clutching or declutching position, as, for example, the end of the rod may be formed with a handle 95 which may be held in a fork 96 when the clutches are to be held out of engagement. 90
- What I claim as my invention is:—
1. In an elevating loader, the combination of a loader frame comprising members forming a tractor-receiving opening; ground wheels supporting the frame; a tractor adapted to propel the loader; and means connecting said tractor to the frame within said opening and in alignment with the frame while permitting it to float up-and-down relative thereto. 100
  2. In an elevating loader, the combination of a loader frame; front steering wheels connected to the frame; rear supporting wheels for the frame; a tractor having its forward end supported solely on the frame and its rear end floatingly connected to the frame. 105
  3. In an elevating loader, the combination of a loader frame; front steering wheels connected to the frame; rear supporting wheels for the frame; a tractor having its forward end supported solely on the frame; and its rear end floatingly connected to the frame with the axes of its master wheels in substantially the same vertical plane as the axes of the rear supporting wheels of the loader frame. 110
  4. In an elevating loader, the combination of a loader frame; front steering wheels connected to the frame; rear supporting wheels for the frame; a tractor having its forward end supported solely on the frame with a universal joint; and a draft connection between the rear of the tractor and the loader frame adapted to float vertically. 120
  5. An elevating loader constructed as set forth in claim 2 in which the support for the forward end of the tractor comprises a transverse yoke; a fore-and-aft pivotal 125

connection between the tractor and the yoke, and open bearings in which the ends of the yoke are receivable and in which they are adapted to turn.

5 6. An elevating loader constructed as set forth in claim 2 in which the draft connection comprises a draw bar secured to the tractor; vertical guides on the frame on which the rear end of the draw bar is slideable, and springs engaging the draw bar and loader frame tending to depress the draw bar.

10 7. In an elevating loader, the combination of a loader frame; ground wheels supporting the frame; a spring suspension between the ground wheels and the frame; a tractor floatingly supported in said frame and adapted to propel the loader.

15 8. In an elevating loader, the combination of a loader frame having a rear gate normally connecting said side members and adapted to be opened up to provide a passage for a tractor; and a tractor floatingly supported within said frame and adapted to propel the loader.

20 9. In an elevating loader, the combination of a loader frame having longitudinal side members; a rear gate normally connecting said side members and adapted to be opened up to provide a passage for a tractor; and a tractor having its forward end detachably and solely supported on the loader frame; and a detachable floating draft connection between the tractor and said gate.

25 10. In an elevating loader, the combination of a loader frame; front steering wheels connected to the frame; rear supporting wheels for the frame; a tractor having its forward end supported solely on the frame and its rear end floatingly connected to the frame; a countershaft journalled on the loader frame above the support for the forward end of the tractor; a sprocket wheel thereon; and a sprocket wheel secured to one of the master wheels of the tractor; and a sprocket chain connecting the two sprocket wheels.

30 11. In an elevating loader, the combination of a loader frame provided with arched longitudinal side members; steering wheels connected with the frame in front of the arch; rear supporting wheels connected with the frame behind the arch; and a tractor having its forward end supported solely on the frame and its rear end floatingly connected to the frame with its master wheels in approximate alinement with the rear supporting wheels.

35 12. In an elevating loader, the combination of a loader frame; ground wheels supporting the frame; a tractor floatingly supported in said frame and adapted to propel the loader; a countershaft journalled on the frame of the loader; a sprocket wheel there-

on; and a sprocket wheel secured to one of the master wheels of the tractor; and a sprocket chain connecting the two sprocket wheels.

40 13. In an elevating loader, the combination of a loader frame; a front axle; a spring suspension between the front axle and the frame; steering wheels suitably carried by the front axle; rear stub axles slidably and resiliently supported on the frame; ground wheels journalled on said stub axles; and a tractor having its forward end supported solely on the frame and its rear end floatingly connected to the frame with its master wheels in approximate alinement with the rear wheels of the loader frame.

45 14. An elevating loader constructed as set forth in claim 13 provided with means for vertically adjusting the front axle.

50 15. In an elevating loader, the combination of a loader frame; a front axle; semi-elliptic springs secured to the front axle; a pivotal connection between one end of each spring and the frame; slides vertically guided on the frame, one for each spring and to which the springs are compensatingly connected; gearing, including a worm and worm wheels, for actuating said slides; steering wheels suitably carried on said axle; and rear wheels suitably journalled on the frame.

55 16. In an elevating loader, the combination of a loader frame; a vertical guide at each side of the rear of the frame; stub axle supporting brackets movable in said guides; stub axles carried by said brackets; and semi-elliptic springs connecting the stub axles and the frame.

60 17. In an elevating loader, the combination of a loader frame provided with front steering wheels and rear wheels; a steering gear for operating the steering wheels; a tractor floatingly connected in said frame and adapted to propel the loader; a pick up drum; an inclined elevator supported on the frame; a transverse conveyor to which the elevator delivers; an operator's platform at the upper end of the conveyor at one side and in front of the transverse conveyor; a control for the steering gear leading to said platform; and controls for the tractor leading to said platform.

65 18. In an elevating loader, the combination of a loader frame provided with front steering wheels and rear wheels; steering gear for operating the steering wheels; a tractor floatingly connected in said frame and adapted to propel the loader; a pick up drum; an inclined elevator supported on the frame; and a transverse conveyor to which the elevator delivers; gearing whereby the tractor actuates the elevator and conveyor; clutch mechanism controlling said gear; an operator's platform at the upper end of the conveyor at one side and in front of the
